UNITED STATES PATENT OFFICE.

JOHN M. BURTON, OF BOSTON, MASSACHUSETTS.

COMBINED DAY AND SLEEPING CAR.

SPECIFICATION forming part of Letters Patent No. 631,418, dated August 22, 1899.

Application filed April 21, 1899. Serial No. 713,903. (No model.)

To all whom it may concern:

Be it known that I, JOHN M. BURTON, of Boston, in the county of Suffolk, State of Massachusetts, have invented certain new and useful Improvements in Railway Sleeping-Cars, of which the following is a description sufficiently full, clear, and exact to enable any person skilled in the art to which it appertains to make and use the same, reference being had to the accompanying drawings, forming part of this specification, in which—

Figure 1 is a side view of the interior of the car, showing one section, the position of the chairs, and the manner of folding up the beds in said section. Fig. 2 is a similar side view of one section of the car interior, showing the manner of making up the upper and lower berths and the position of same when in use. Fig. 3 is a vertical transverse section of the 20 chairs composing the end of a section. Fig. 4 is a horizontal section taken near the top of said chairs, showing the construction and mechanism of the upper berth. Fig. 5 is a 25 side elevation showing the upper berth in position for use and a means for locking the two-part berth together. Fig. 6 is a cross-section of one of the bed-frames.

Like letters and numerals of reference indicate corresponding parts in the different views 30 of the drawings.

My invention relates especially to an improvement in railway sleeping-cars; particularly in the construction of the chairs and the manner of making up the beds or berths with 35 said chairs.

I aim to supply a device applicable to cars already in use in regular passenger service safe and easy to adjust, combining at night all of the comforts of the most luxurious 40 palace sleeping-car at a minimum of expense to railroad companies and the traveling public.

The nature and operation of the improvement will be readily understood by all conversant with such matters from the following 45 explanation.

In the drawings, Fig. 1, are represented the double chairs composing what is known as "one section" in a sleeping-car. In general appearance and position these chairs do not 50 differ from those now in use. In place of the cushions forming the backs of the chairs or seats in the usual construction I substitute a

flexible covering A, of plush or other material, inclosed within a frame and hinged to a rod F. Said flexible covering is adapted to be swung 55 up to a perpendicular position to form a partition between that and the adjoining section. Said covering A also serves as a shield to a bed-frame containing a mattress E beneath it. The frame J J J and W is shown in Fig. 6 60 and c c in Fig. 3. Said frame is hinged at its upper extremity to the pipe P by means of the bands G. Said frame and mattress is adapted to be swung upward to a horizontal position to meet a similar swinging bed-frame 65 and mattress similarly arranged at the opposite end of the section, and by means of a locking mechanism the said two swinging bed-frames and mattresses are joined and locked when raised to a horizontal position and complete the upper berth. 70

Each section of the upper-berth frame is provided with a movable head-rest M, supported upon the pipe P by means of the straps O, and is pivotally arranged upon the 75 shaft X. Sufficient space is afforded to allow the rest M to swing to an inverted position when not in use. The bed-frames of the upper berths are supported upon the pipes P through the medium of the straps G. The 80 pipes P rest in countersunk collars U in the wood standards I. The pipes P are provided with rods H, movable and extending the full length of the pipes P. Sleeved upon the rods H are serrated circular pieces V, which are 85 riveted to the pipe P through the medium of springs N and rod H. Similar serrated pieces engage with the serrated piece V to hold the berth at any position on its upward movement and are disengaged by a movement of 90 the rod H through the pipe P.

The bed-frames, both sides and bottom, are preferably of wood. At each end of the bed-frame sides is fastened a small metal casting. Secured to the castings are a series of 95 metal bars J for strengthening the bed-frames. The metal bars J also serve as a shield to the jointed folding extension-bar 2, which locks the bed-frame together.

In Fig. 5 is shown a means of locking the 100 beds composing the upper berth together, and it consists of a metal bar K, which is inclosed by the bed-frame W, and metal bars J. (See Fig. 6.) Said bar K is provided with

a jointed swinging extension 2, adapted to enter a corresponding recess in the opposite bed-frame when raised horizontally, and thus form a secure and safe lock to the upper 5 berth, and when not employed for this purpose the jointed extension can be folded within the frame W and J J J beneath the bar K.

The stationary seats are securely fastened to the sides of the car and floor. Sufficient 10 space remains beneath the car-seats and in the car sides to store all necessary bedclothing. Many travelers prefer to remain dressed at night on board cars, and those averse to paying exorbitant rates for the privileges 15 now afforded in many instances would carry their own blankets. An ordinary passenger-car fifty feet long carries fifty-six passengers. The same car can be equipped with the invention described and accommodate the passengers both day and night.

Having thus explained my invention, what I claim is—

1. In a railway-car seats having movable swinging backs comprising one part of a bed-frame and mattress and a flexible covering adapted to be raised to a perpendicular position to form a dividing-partition between the berth-sections and when lowered to form a covering and shield to the bed-frame and mattress substantially as and for the purpose specified.

2. In railway-car seats the backs thereof provided with an exterior flexible shield or covering adapted to be swung up to a perpendicular position to form a dividing-partition between the sections of a car when used as a sleeping-car substantially as set forth.

3. In combination with the seat-cushions

of a railway-car the shield or supplementary cushion A substantially as and for the purpose specified.

4. In the chairs of a railway-car the combination of the separating-partition D swinging bed-frame C and W mattress E and flexible covering A substantially as and for the purpose specified.

5. In a railway-car seats having movable backs which form upper berths when raised horizontally in pairs flexible partitions forming the exterior of the movable backs and mechanism for locking the berths together substantially as and for the purpose specified.

6. In a sleeping-car in combination with movable beds forming the backs of car-seats the supporting-pipes P rods H and serrated 55 engaging couplings Z and V substantially as and for the purpose specified.

7. Sleeping-car seats having hinged swinging bed-frames in combination with the folding extension-bar 2 metal bars J and side 60 pieces W substantially as and for the purpose specified.

8. In sleeping-car seats having hinged movable backs in combination with the bed-frames the mattress E pivoted head-rest M and 65 flexible shield A substantially as described and for the purpose specified.

In testimony whereof I have signed my name to this specification, in the presence of two subscribing witnesses, on this 17th day 70 of April, A. D. 1899.

JOHN M. BURTON.
